United States Patent Office

Des. 189,340
Patented Nov. 29, 1960

189,340

HANDLE FOR WINDOWS

Harry M. Riegelman, Rolling Hills, Calif., assignor to Security Aluminum Corporation, Compton, Ill., a corporation of California

Filed Jan. 18, 1960, Ser. No. 59,079

Term of patent 14 years

(Cl. D10—8)

Figure 1 is a perspective view of a handle for windows embodying my new design, an associated window frame being shown fragmentarily in phantom lines for purpose of illustration and the handle of my new design being shown in locking position with respect thereto;

Figure 2 is a front elevational view of the handle shown in Figure 1; and

Figure 3 is a top plan view of the handle shown in Figure 1.

I claim:

The ornamental design for a handle for windows, as shown and described.
